CLAIM

The ornamental design for mixing tap with a spray head, as shown and described.

DESCRIPTION

FIG. 1 is a perspective view, taken from the front and above, of a mixing tap with a spray head and shows the spray head in its inserted position;

FIG. 2 is a perspective view thereof taken from below;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof;

FIG. 8 is a perspective view thereof, taken from above, and shows the spray head in an extended position;

FIG. 9 is a front perspective view, taken from below, and shows the spray head in an extended position; and,

FIG. 10 is a left side elevational view thereof showing the spray head in an extended position.
